UNITED STATES PATENT OFFICE.

ALFRED RELAY, OF SOUTH NORWALK, CONNECTICUT, ASSIGNOR OF ONE-THIRD TO WILLIAM A. GUNTHER, OF SAME PLACE.

RAIL-JOINT.

SPECIFICATION forming part of Letters Patent No. 655,370, dated August 7, 1900.

Application filed October 16, 1899. Serial No. 733,718. (No model.)

To all whom it may concern:

Be it known that I, ALFRED RELAY, a citizen of the United States, and a resident of South Norwalk, county of Fairfield, and State 5 of Connecticut, have invented certain new and useful Improvements in Rail-Joints, of which the following is a specification, reference being had to the accompanying drawings, forming a part thereof, in which similar 10 characters of reference indicate corresponding parts.

This invention relates to improvements in railroad-rail joints; and the object thereof is to provide an efficient means for connecting 15 the rail-sections without the necessity of using bolts or nuts, whereby liability of accidental separation of the rail-sections is obviated.

The invention will be hereinafter fully described, and specifically set forth in the 20 annexed claims.

In the accompanying drawings, forming part of this specification, Figure 1 is a perspective view illustrating two rail-sections disconnected. Fig. 2 is a side elevation showing the sections connected; and Fig. 3 is a similar view showing the fish-plates forming part of the structure in permanent position, whereby the two rail-sections are locked to each other.

30 In the practice of my invention the rail-section A is provided with a projection a, having a recess a' therein, whereby a hook is formed. The adjacent rail-section B is provided with a recess b of a contour adapted for engagement with the projection a. Within this recess is formed a lug b', which engages the recess a' when the two sections of rail are connected to each other. From the base of the rail-section A is extended a platform A', 35 which engages a recess B' in the base of the rail-section B.

In the drawings I have only shown a small portion of the rail-sections; but it is obvious that each section is provided at one end with 40 a recess and at the other end with a projection for engaging said recess.

Slidably mounted upon the rail-section A

at each side of its vertical web is a fish-plate C, each fish-plate being provided with a tongue c upon its respective upper and lower edges. 50 These tongues engage grooves d, located, respectively, in the tread and base-flange of the rail-section A. Similar grooves e are formed in the rail-section B for engaging the fish-plates when the two sections are connected 55 to each other.

In connecting the rail-sections they are interlocked by moving them laterally toward each other until they are in perfect alignment, as illustrated by Fig. 2 of the drawings. The fish-plates C are then forced within the grooves e, whereby the two sections are securely connected to each other and lateral displacement is prevented. The fish-plates fit snugly within the grooves d and e, and it 60 is believed that they will remain in position after they are locked; but to avoid any liability of accidental sliding movement the grooved portion at 1, Fig. 3 of the drawings, may be filled up with lead or other material. 65

Having thus described my invention, what I claim as new, and desire to secure by Letters Patent, is—

1. In a rail-joint the combination with one rail-section having an extended platform and 75 an extended projection with a recess therein, of a rail-section having a recess in its web, a recess in its base and an upwardly-extended lug in the recess in its web, substantially as shown and described.

2. In a rail-joint, the combination of the rail-section A, its recessed extension a and its platform A', with the rail-section B and its recesses B' and b, substantially as shown and described.

85 In testimony that I claim the foregoing as my invention I have signed my name, in presence of two witnesses, this 7th day of October, 1899.

ALFRED RELAY.

Witnesses:

JAMES PAUL,

FRANK D. LAYTON.
